(57) **CLAIM**

The ornamental design for a device for measuring ocular parameters as shown and described.

DESCRIPTION

1. Device for measuring ocular parameters

1.1 : Perspective

1.2 : Front

1.3 : Back

1.4 : Left

1.5 : Right

1.6 : Top

1.7 : Bottom

The broken lines depict portions of the device for measuring ocular parameters that form no part of the claimed design. The name of the product incorporating the design: Device for measuring ocular parameters; The use of the product incorporating the design: The product incorporating the design is used for measuring ocular parameters; The essential features of the design: The essential features lie in the shape of the product shown in the drawings; The drawing elected to best show the essential features of the design: the perspective view.

1 Claim, 7 Drawing Sheets
